JAMES KEITH AND DAVID BALFOUR BAIN, OF LONDON, ENGLAND.

APPARATUS FOR HEATING OR COOLING AIR.

1,149,065.

Specification of Letters Patent.

Patented Aug. 3, 1915.

Application filed March 5, 1914. Serial No. 822,670.

To all whom it may concern:

Be it known that we, JAMES KEITH and DAVID BALFOUR BAIN, subjects of the King of the United Kingdom of Great Britain and Ireland, and residents of London, England, have invented a certain new and useful Improvement in Apparatus for Heating or Cooling Air, of which the following is a specification.

10 This invention relates to tubular apparatus for heating or cooling air for ventilating or the like, said apparatus comprising a casing containing inclined heat exchanging elements, over which a current of 15 air is caused to pass by means of a fan.

In the accompanying drawings, Figures 1 and 2 are vertical sections showing alternative forms of apparatus embodying the present invention applicable mainly for 20 heating or cooling and ventilating the cabins of ships.

The same reference characters denote similar parts in the several views.

As shown, the apparatus employed comprises a main casing A situated above and communicating with a fan casing. The said main casing A, which is of approximately cylindrical formation, is fitted with an annular header H carrying inclined upwardly extending heat exchanging U tubes G around which travels the current of air entering through an inlet covered by a protecting cowl F. Situated below the header in the under part of the casing is a centrifugal fan runner D mounted on a vertical shaft driven by a motor E below, the air being delivered downwardly from the fan casing into the duct C.

It will be understood that the U-tubes 40 constituting the heat exchanger inclose a hollow space in which is fitted a baffle device K.

The modification represented at Fig. 2

is similar to that shown at Fig. 1 excepting that the fan runner and the armature 45 of the motor rotate on a horizontal axis, the air being led into the eye of the casting of the fan D by a duct J and being delivered from the fan casing to the duct C. As is evident, the air flows twice through 50 the space between any two adjoining tubes in intersecting the surface of the hyperboloid of revolution containing the tubes.

In both cases the tubes are disposed at an inclination in relation to the direction 55 of flow of the air to be heated, whereby the condensed vapor is caused to flow downward so as to leave comparatively dry the surface of the tubes directly acted upon by the air in its passage, thereby greatly increasing the efficiency of the apparatus.

We claim:

Apparatus for heating or cooling air, comprising, in combination, a main casing, a fan casing in communication with said main casing, a centrifugal fan runner mounted to rotate in said fan casing and adapted to produce a current of air through said main casing, a heat exchanger comprising U-tubes contained in the surface of a 70 hyperboloid of revolution and inclosing a hollow space, and a baffle device in said hollow space, said U-tubes exposed to repeated impact by the air current, each tube disposed at an inclination to the horizontal, and at 75 an inclination to the direction of flow of the air propelled by said fan, as and for the purpose specified.

In testimony whereof we have signed our names to this specification in the presence 80 of two subscribing witnesses.

JAMES KEITH.

DAVID BALFOUR BAIN.
